UNITED STATES PATENT OFFICE.

AUGUST STEINER, OF HOMEWOOD, ILLINOIS.

BALE-TYING MACHINE.

SPECIFICATION forming part of Letters Patent No. 236,191, dated January 4, 1881.

Application filed September 24, 1880. (No model.)

To all whom it may concern:

Be it known that I, AUGUST STEINER, of Homewood, in the county of Cook and State of Illinois, have invented a certain new and useful Improvement in Bale-Tying Machines, of which the following is a specification.

In securing bales by wire bands the ends of which are fastened by twisting them together, with the machines heretofore used it has been the custom to draw the wire as tight as possible by hand through the slots of the tying-machine; but this can only be done imperfectly, and consequently the bales are allowed to expand considerably by reason of the looseness of the wire. This expansion not only enlarges the bales, so that they require more room for transportation, but, being very sudden in its action, it strains and often breaks the wires or pulls out the fastenings.

Now, it is the object of my invention to produce a bale-tying machine for twisting together the ends of wire bands, which will have means for drawing the wire tight before the ends are twisted, and will be so constructed that it can be easily removed from the bale after the twisting has been effected. My machine at the same time is stronger and more durable in construction than that heretofore used, has means for guiding the wires throughout the length of the twist, and makes a more secure lock.

My invention consists in the several novel devices and combinations of devices employed by me, as fully hereinafter explained, and 35 pointed out by the claims.

In the accompanying drawings, forming a part hereof, Figure 1 is a side elevation of the machine with the tightening-lever in position for drawing the wire taut before the twist is made, the twist, however, being shown, for convenience of illustration, as completed; Fig. 2, an edge elevation of the machine with the crank-brace removed and the tightening-lever thrown down; Fig. 3, a sectional view through the slots of the machine; Fig. 4, a view of one of the end holding plates, the end of the journal-box and one of the curved holding-spikes being shown in dotted lines; and Fig. 5, a sectional view through a portion of the frame, 50 showing the construction of the spring-catch.

Like letters denote corresponding parts in all five figures.

A is the frame of the machine, made preferably in two parts clamped together, and forming the bearing *a* for the shaft *B*. The shaft *B* is turned by a crank-brace, *C*, secured to the outer end of the same, while the inner end of the shaft *B* carries a bevel cog-wheel, *D*. The frame *A* has laterally-projecting boxes *E* *F* at its ends, which boxes receive the ends of a shaft, *G*, connecting them, and abutting endwise against shoulders *b* in said boxes. The shaft *G* has a bevel-gear, *H*, cast therewith or secured thereto, and situated below the center of said shaft, for a purpose which will be presently explained. The shaft *G* has a slot, *I*, extending through one side to its center and running the whole length of the shaft. This slot also extends through the cog-wheel *H*, and the boxes *E* *F* have corresponding slots. The slot *I* is slightly larger than two wires laid together, except at the gear-wheel *H*, where the slot is contracted laterally, as shown by *c*, to the width of one wire, so that two wires cannot turn therein past each other.

The boxes *E* *F* are provided with slotted steel plates *d* *d'*, the slots *e* of which are also contracted to the size of a single wire. The slots *e* of the plates *d* *d'* and those of the boxes are arranged obliquely, as shown in Fig. 4, 80 and the holding-spikes *f* of the machine are curved, as shown, the object being to allow the machine to be removed from the bale by turning the slots toward the bale, the wire being freed from the machine by this movement.

The upper end of the frame *A* is extended beyond the box *E*, and has journaled therein a short shaft, which carries a flat-faced wheel or segment of a wheel, *K*. This wheel is arranged about at right angles to the slot in the upper plate, *d*, and above and to one side of the same. It has a stud, *g*, on its face and a pivoted dog, *h*, which dog has a serrated end and swings against said stud in one direction. This dog is adapted to hold the end of a wire securely by jamming it against the stud *g*. A hand-lever, *L*, is secured to the end of the shaft of the wheel *K*, and a spring-catch, *i*, on the frame *A* locks this hand-lever in its lowest position.

In use the spikes of the machine are forced into the sides of the bale while in the press at the location of the meeting and lapping ends of one of the wire bands. These ends are laid

in the slots of the machine, and the downwardly-projecting end of the wire is bent across the face of the lower plate, d' , to prevent slipping. The lever L is thrown up and the upwardly-projecting end of the wire is locked by the dog h and stud g to the wheel K . The lever is then thrown down, and the wire band is drawn tightly around the bale. If the first throw of the lever does not draw the band tight enough the lever can be moved up and the wire caught at a point farther down. The lever is forced over the catch i and holds the wire taut while the ends are being twisted. The twisting is accomplished by turning the crank-brace C the desired number of times. The lock being completed, the wire is released from the dog h and the machine is turned out of the bale, as before explained, and placed in position for locking the next wire band.

Bales secured in this manner (by drawing the wires tight before the ends are twisted together) do not expand, and therefore require less room for transportation, and, as before explained, the locked ends of the wires are not so liable to be pulled apart.

By having the twisting-gear H located on one side of the center the twists of one half of the lock will be shorter and closer together than those of the other half. The spirals of the lock not corresponding in pitch, the lock cannot so readily untwist as if such spirals were all of the same pitch.

The shaft G extending the entire distance between the boxes $E F$, the wire ends are supported and guided throughout the length of the twisted portion, and a much smoother and uniform twist is the result. The twisting shaft, having two bearings, is also better supported and works with less friction and wear.

What I claim as my invention is—

1. The combination, with a bale-tying machine whereby the ends of wire bands are twisted together, of means, substantially as described, for tightening the wire before the twist is made.

2. In a bale-tying machine, the combination, with the twisting and holding slots, of a lock for holding the end of the wire and a lever for throwing such lock away from the slots of the machine, so as to draw the wire taut, substantially as described and shown.

3. In a bale-tying machine, the combination, with the twisting and holding slots, of the wheel K , having means for holding the end of the wire, and the lever L , for turning such wheel, substantially as described and shown.

4. In a bale-tying machine, the combination, with the twisting and holding slots, of the wheel K , having stud g and pivoted dog h , the lever L , and the spring-catch i , substantially as described and shown.

5. In a bale-tying machine, the combination, with the boxes $E F$, having holding-slots, of the slotted twisting-shaft G , journaled in both of said boxes, and the twisting-gears $D H$, substantially as described and shown.

6. In a bale-tying machine, the combination, with the slotted twisting-shaft G and gears $D H$, of the boxes $E F$, having oblique holding-slots, and the curved spikes f , substantially as described and shown.

7. The bale-tying machine described, having in combination the crank-brace, the bevel-gears, the slotted shaft, slotted boxes, tightening wheel and lever, and the holding spikes, all substantially as set forth and shown.

AUGUST STEINER.
